ADDRESSING MACHINE

Frank V. Moore, Los Angeles, Calif., assignor to
John M. Alford, Galva, Ill.

Application May 22, 1941, Serial No. 394,610

11 Claims. (Cl. 101—274)

My invention relates to an addressing machine, and more particularly to a machine from which names and addresses are printed from prepared plates.

An object of the invention is to provide a simple, practical addressing machine of such character that may be economically built for general commercial purposes.

Another object of the invention is to provide means for holding a roller carriage down firmly in a position to effect printing from a plate fed from a supply of plates.

My invention also has for its objects to provide an addressing machine that is positive in operation, convenient in use, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a plan view of an addressing machine embodying features of my invention.

Fig. 2 is a broken underneath view of such embodiment.

Fig. 3 is a broken perspective view of such embodiment.

Fig. 4 is a section taken on the line 4—4 of Fig. 1.

Fig. 5 is a rear view of operating mechanism, taken in the direction of the arrow 5 of Fig. 4.

Figs. 6 and 7 are views similar to Fig. 4, but showing the machine in different operating positions.

Fig. 8 is a section taken on the line 8—8 of Fig. 6.

Fig. 9 is a section taken on the line 9—9 of Fig. 6.

Fig. 10 is a perspective view of a detail comprised in the invention.

Fig. 11 is a sectional detail which will be more fully described hereinafter.

Fig. 12 is an enlarged broken section taken on the line 12—12 of Fig. 5.

Fig. 13 is a horizontal section, partly broken away, taken on the line 13—13 of Fig. 12.

Fig. 14 is a section looking in the direction of the arrows 14—14 of Fig. 12.

Fig. 15 is a broken section taken on the line 15—15 of Fig. 12.

Fig. 16 is a section taken on the line 16—16 of Fig. 15, but showing a ribbon on the spool.

Fig. 17 is a perspective of an element of the ribbon reversing mechanism.

5 Fig. 18 is a section taken on the line 18—18 of Fig. 2.

Referring more in detail to the drawings, the reference numbers 18 and 19 generally designate front and rear legs, respectively, having feet 20 and 21. A platform 22 is arranged at the side of the addressing machine 23, for feeding address plates 24 to the machine. A container 25 is provided on the platform 22 for a supply of the plates 24. A receiving container 26 is provided at the opposite side of the addressing machine 23, for receiving plates 24 that have been printed.

Means for manually feeding the plates 24 successively comprises a lever 27 that is fulcrumed at 28. A return spring 29 tends to resist advancing movement of the lever 27 and tends to return it to its original position. The fulcrum 28 is provided on a bracket 30 on the frame 31 of the machine. The bracket 30 also aids in supporting the platform 22.

25 A feeding carriage 32 is mounted to slide upon a track 33. Fingers 34 are mounted on arms 142, which arms are pivoted upon a cross rod 141 on the carriage 32. A flat spring 140 is arranged with its ends under the arms 142. The spring 140 tends to raise the arms, and thereby the fingers 34, to a position in which the fingers project through slots 35 in the platform floor. The spring 140 permits a downward yielding of the arms 142 and the fingers 34, upon the return movement of the carriage 32 to its original position: engaging the edge of the bottom plate. The fingers 34 successively engage an edge of the lowermost plate 24 and move it to the left in Figs. 1 and 2. A bolt 36, mounted on the carriage 32, pivotally connects with the lever 27 by means of a slot 37, whereby swinging movements of the lever 27 produce reciprocal movements of the carriage 32, to feed successive plates to the machine.

The plates 24 have identifying head members 45 38 attached to the printing portion 39 of the plate. A mask 40 is bolted to the platform 22, and provides windows 41 through which the head members 38 of the plates may be viewed as the plates are fed to the addressing machine 23. The mask 40 provides an upper guide, as shown in Fig. 1, while a lower guide 42 is bolted opposite same for guiding the lower edge of the plates 24, as they are viewed in Fig. 1. A stop 43 limits the return movement of the lever 27. This stop 43 also provides a supporting leg for the platform 22.

The addressing machine comprises a frame 44 provided with upstanding lugs 45 upon which a roller carriage 46 is pivoted by means of a pin 47. The carriage 46 has an integral finger 48 projecting from the opposite side of the pin 47. A relatively fixed finger 49 on the frame 44 provides a fixed attachment for a spring 50, which is also connected with the finger 48. The spring 50 tends to move the roller carriage 46 to the open position shown in Fig. 4.

Pivottally mounted on the roller carriage 46 is a handle 51. An arm 52 at the opposite side of the pivot 53 from the handle 51, is pivotally connected with roller supporting arms 54. An impression roller 55 is mounted on the arms 54 for free rotation. The impression roller 55 is a resilient rubber composition for producing an even impression from a printing plate 24. The shaft 56 of the roller 55 rides upon tracks 57 at either side of the head 58 of the roller carriage 46. Suitable nuts 59 are employed to maintain the track rails 57 in their operative position. Where it is desired to cause the roller 55 to engage a wider or narrower area on the printing plate 24, longer or shorter track rails 57 are substituted for those shown. Adjusting screws 60 are arranged to adjust the track rails 57 in vertical planes.

Pivottally mounted on a lug 61 on the head 58 is an arm 62 that is provided with a shoulder 63. Spaced pins 64 and 65 on the arm 52 provide limits for the swinging movement of the arm 62. When the carriage head 58 is in the raised position, shown in Fig. 4, and the handle 51 is likewise in a raised position, the shoulder 63 of the arm 62 is engaged by the pin 64. This causes the handle 51, the carriage 46 and the roller 55 to be locked with respect to one another, while the carriage and roller are being lowered to a printing position. When the carriage and roller reach the printing position, the roller 55 is released to roll across the printing plate. Fig. 6 shows the arm 62 just after it has been released and the printing roller 55 is beginning to roll across the printing plate. Fig. 7 shows the position of the addressing machine at the completion of the printing operation.

An H-shaped rocker 66 is pivoted on the pin 67 mounted in a boss 68 on the frame 44 of the machine. An adjusting screw 69 limits the inward movement of the rocker 66 toward the frame 44. A spring 70 tends to draw the rocker 66 toward the frame 44. A bolt 71 fastens an end of the spring 70 to the rocker 66. A coil spring 72 tends to return the handle 51 to its original raised position, as shown in Fig. 4.

The carriage 46 also has integral fingers 73 and 74 which project rearwardly from the pin 47. The inner face of the upper ends of the rocker 66 are bevelled as shown at 75. The rear, squared faces of the fingers 73 and 74 slide upward on these bevelled faces 75 as the carriage head 58 descends toward the printing plate. When the carriage head 58 has been moved to the printing position shown in Fig. 6, the spring 70 draws the rocker 66 under the ends of the fingers 73 and 74, thus blocking the carriage head 58 down in its printing position.

An angular sliding plate 76 is slidably held on under side of the carriage 46 by means of a bolt 77 arranged in a slot 78 in the plate. An adjusting screw 79 provided with a lock nut 80, is threaded through a flange 81 at the end of the slide plate 76, and abuts against a vertical inner face of the rocker 66. The screw 79 will

adjust the release of the arm 62 since an angular abutment member 82 fastened to the slide 76 by means of a screw 83, engages the outer, cam end of the arm 62. As soon as the carriage head 58 has been moved to the printing position, and the rocker 66 has been locked under the fingers 73 and 74, the bevelled end of the arm 62 strikes the abutment 82, thus raising the arm 62 to disengage the shoulder 63 from the pin 64. Thereupon, the roller 55 may be moved across the printing plate by further depressing the handle 51.

To provide automatic advancing of the ribbon, a leg 84 is mounted on the side of the finger 73. The leg 84 has a notched lower end 85. A reciprocating bar 86 has a pin 87 engaging the notch 85. The bar 86 has a longitudinally arranged rod 88 which reciprocates in a recess 89 in one of the front legs 18.

The bar 86 carries pivoted dogs 90 and 91. The dogs are connected by a spring 92 which tends to swing the dogs toward each other. The dog 90 has a tooth 93 for engaging a ratchet 94 on a ribbon spool 95, while the dog 91 has a tooth 96 to engage a ratchet 97 on a ribbon spool 98. During each depression and return of the carriage head 58, the leg 86 reciprocates to and from the broken line position shown in Fig. 12. This reciprocation causes the dog that is engaged with a ratchet, to advance the ratchet and thereby advance the ribbon 99 upon the respective spool.

Manual means for changing the direction of movement of the ribbon comprises a handle 100 on a sliding bar 101 movable along the bar 86. Lugs 102 on the bar 101 are bent over the top of the bar 86, to maintain the bar 101 in relation to the bar 86. For the same purpose a screw 103 on the bar 86 engages a slot 104 in the bar 101. Lugs 105 and 106 on the bar 101 are bent around under the bar 86. Movement of the lugs 105 and 106 to the left in Fig. 12 would move the dog 90 into engagement with the ratchet 94 (as shown in broken lines) and permit the lug 106 to move the dog 91 out of engagement with the ratchet 97 (also shown in broken lines). The movement of the dogs away from the respective ratchets is against the action of the spring 92. Causing the ribbon to move in the opposite direction is effected by moving the bar 101 and thereby the lugs 105 and 106 to the position shown in Fig. 12.

Means for fastening the ribbon 99 on the spools includes a rod 107 that is mounted between the ends of the spool in laterally spaced relation to the shaft 108 of the spool. The ribbon is fed between the rod 107 and shaft 108, and then the ribbon is folded back on itself, as shown at 109, with a rod 110 arranged in the fold. This is best shown in Fig. 16. The rod 110 is sufficiently large to prevent the folded ribbon from slipping between the rod 107 and the shaft 108.

The shaft 108 of the spool is hollow with a spindle 112 passing through same. An enlarged threaded neck 113 of the spindle 112 provides means for screwing the spindle 112 into the frame 44 of the machine. An knurled head 114 for the spindle 112 may be provided.

A guide 115 limits the inward movement of sheets of paper or envelopes which are addressed on the present machine. The guide 115 has flanges 116 that are slotted at 117 for receiving adjusting screws 118. A lug 119 is provided on the sliding plate 76 to limit lateral movement of

the plate 16 away from the under side of the finger 74.

A flat tension spring 120 has its ends engaging the heads of the spools 95 and 98, to prevent unrolling of the ribbon from the spools until driven. A printing shield 121 is provided for sliding envelopes or sheets of paper into the machine. The shield 121 has a window 122, where the ribbon appears superimposed upon the printing plate.

It is to be understood that at least one side of the carriage has a curved shoulder 130 which serves as a track for sliding movements of a pin 131 on a lug 132 on one of the arms 54. This shoulder 130 and pin 131 maintain the roller 56 on the rails 57.

In the operation of my machine, a supply of addressing plates 24 is inserted in the container 25. The plates are successively fed into the machine by means of the feeding carriage 32, 20 which is manipulated by the lever 27. As the printing plates are successively removed from the bottom of the stack in the container 25, they push forward into the machine the preceding plates, inasmuch as the plates are alined with 25 their edges abutting.

When the desired plate is pushed under the shield 121 in such a position that the type on the plate is opposite the window 122, the envelope or sheet of paper is inserted under the 30 printing head 58 until it is in engagement with the guide 115. Thereupon, pressure is applied to the handle 51 in a downward direction. The initial part of this movement causes the rocking carriage 46 to be moved down to a printing position, such as shown in Fig. 6. In this position the rocker 66 is swung under the fingers 73 and 74, by means of the spring 70, in order to lock the printing head 58 in its lowered, printing position.

As the rocker 66 is swung inward toward the frame of the machine, it engages the screw 79 extending through the lug 81 on the sliding plate 76 and pushes the abutment 82 against the bevelled, cam end of the arm 62. This movement takes place after the rocker 66 has been moved to a locking position under the fingers 73 and 74.

After the arm 62 has been released from the pin 64, by the abutment 82 on the sliding plate 76, further downward movement of the lever 51 causes the roller 55 to be drawn across the rear of the envelope or sheet to be printed, thus causing an impression of the type, through the ribbon, upon the face of the envelope or sheet of paper. Toward the end of the printing movement of the roller 55, the arm 52 strikes an abutment 124 on the sliding plate 76, causing a rearward sliding movement of the plate 76, which moves the rocker 66 out from under the fingers 73 and 74. Then, upon release of the handle 51, the springs 50 and 72 return the printing carriage 46 and the handle 51 to their original positions. Then, another printing plate is fed forwardly under the printing carriage 46 and the cycle of operation is gone through again. The plate just printed from is ejected to the left of the addressing machine into a box 26 for the used addressing plates.

The ribbon is fed forwardly as successive plates are printed, by means of the leg 84 reciprocating the bar 86. Upon each of these reciprocations, one of the spools is advanced, by reason of the ratchet on the spool and the engaging pivoted dog on the bar 86, and at the same time withdrawing the ribbon from the other spool.

The direction of movement of the ribbon 99 is manually reversed by longitudinal movement of the bar 101 through the intermediary of the handle 100. When a new ribbon is wound upon the spools, the end of the ribbon is folded upon itself, as suggested at 109, with a rod 110 within the fold, in order to anchor one end of the ribbon upon the spool.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications which may fall within the scope of the appended claims.

Having thus described my invention, what I claim and desire to secure by Letters Patent is:

1. In an addressing machine, a frame having a printing area, a carriage pivoted to the frame to swing to and from a printing position, means to lock the carriage when it is swung to a printing position, a printing roller, means to roll the roller across the printing area, and mechanism controlled by the roller rolling means arranged to release the locking means substantially at the end of the printing operation.

2. In an addressing machine, a frame having a printing area, a carriage pivoted to the frame to swing to and from a printing position, a rocker on the frame arranged to rock to a locking position with respect to the carriage, when the carriage is swung to a printing position, a printing roller, means to roll the roller across the printing area, and mechanism controlled by the roller rolling means arranged to release the rocker substantially at the end of the printing operation.

3. In an addressing machine, a frame having a printing area, a carriage pivoted to the frame to swing to and from a printing position, means to lock the carriage when it is swung to a printing position, spring means urging the locking means to a locking position, when the carriage is swung to a printing position, a printing roller, means to roll the roller across the printing area, and mechanism controlled by the roller rolling means arranged to move the locking means to an unlocking position, against the action of said spring means, substantially at the end of the printing operation.

4. In an addressing machine, a frame having a printing area, a carriage pivoted to the frame to swing to and from a printing position, means to lock the carriage when it is swung to a printing position, spring means urging the locking means to a locking position, when the carriage is swung to a printing position, a printing roller, means to roll the roller across the printing area, and a sliding member arranged on the carriage to be slid thereon by movement of the roller rolling means, said member being arranged for its sliding movement to move the locking means to an unlocking position, against the action of the spring means, substantially at the end of the printing operation.

5. In an addressing machine, a frame, a carriage movable on the frame to and from a printing position, a roller mounted to roll across the carriage when the latter is in a printing position, mechanism to lock the roller with respect to the carriage during movement of the carriage to a printing position, means to lock the carriage in the printing position, and means to release the

roller locking mechanism connected to be actuated by the carriage locking means during locking movement of the latter means.

6. In an addressing machine, a frame, a carriage movable on the frame to and from a printing position, a roller mounted to roll across the carriage when the latter is in a printing position, a manipulating handle connected to move the carriage to a printing position and to move the roller across the carriage when the latter is in a printing position, mechanism to lock the handle, the roller and the carriage with respect to one another during movement of the carriage to a printing position, means to lock the carriage in the printing position, and means to release the handle-roller-carriage locking mechanism connected to be actuated by the carriage locking means.

7. In an addressing machine, a frame, a carriage movable on the frame to and from a printing position, a roller mounted to roll across the carriage when the latter is in a printing position, a manipulating handle connected to move the carriage to a printing position and to move the roller across the carriage when the latter is in a printing position, mechanism to lock the handle, the roller and the carriage with respect to one another during movement of the carriage to a printing position, means to lock the carriage in the printing position, means to release the handle-roller-carriage locking mechanism connected to be actuated by the carriage locking means, and the roller being connected substantially at the end of the printing operation to actuate said releasing means to release the carriage locking means.

8. In an addressing machine, a frame, a carriage movable on the frame to and from a printing position, a roller mounted to roll across the carriage when the latter is in a printing position, a manipulating handle connected to move the carriage to a printing position and to move the roller across the carriage when the latter is in a printing position, mechanism to lock the handle, the roller and the carriage with respect to one another during movement of the carriage to a printing position, means to lock the carriage in the printing position, a reciprocating member arranged on the carriage to be reciprocated thereon, the carriage locking means being arranged to actuate movement of said member in one direction, releasing the handle-roller-carriage locking mechanism, and the handle being connected to reciprocate said member in the opposite direction, substantially at the end of the printing operation, releasing the carriage locking means.

9. In an addressing machine, a frame, a carriage movable on the frame to and from a print-

ing position, a roller mounted to roll across the carriage when the latter is in a printing position, a manipulating handle connected to move the carriage to a printing position and to move the roller across the carriage when the latter is in a printing position, mechanism to lock the handle, the roller and the carriage with respect to one another during movement of the carriage to a printing position, means to lock the carriage in the printing position, spring means resisting movement of the carriage to a printing position, spring means resisting effective movement of the roller across the carriage in a printing position, spring means resisting movement of the carriage locking means from a locking position, a reciprocating member arranged on the carriage to be reciprocated thereon, the carriage locking means being arranged to actuate movement of said member in one direction, releasing the handle-roller-carriage locking mechanism, and the handle being connected to reciprocate said member in the opposite direction, substantially at the end of the printing operation, releasing the carriage locking means.
